UNITED STATES PATENT OFFICE.

GEORGE EUGENE MITTINGER, OF CLEVELAND, OHIO.

KEG, BARREL, AND THE LIKE.

Application filed July 15, 1925. Serial No. 43,809.

This invention relates to improvements in kegs, barrels and the like and it pertains to improvements in the construction of the metallic head, and in the wooden staves of 5 which the receptacle is composed.

The present invention is to supply a receptacle particularly intended as a shipping receptacle for bolts, nuts, rivets, screws, etc., thus making its contents of heavy material 10 which necessarily can not be tightly packed, and thus in handling has some movement which brings the whole weight of its contents or bulk at times on the head.

In handling a shipping package it is 15 sometimes dropped from a platform or less height, and is at times exceedingly roughly handled, which shifts the entire bulk of its contents upon one end of the receptacle, it is necessary that the construction be such 20 that the staves will not break or the cover be knocked loose thus spilling its contents.

Therefore the primary object of the present invention is to so construct the staves 25 and the head as to give a maximum strength to each of them, whereby when the same is dropped as aforesaid, neither the staves nor its cover will be either broken or knocked loose, which is liable to happen when the receptacle falls in certain positions.

30 Heretofore wooden receptacles for containing the materials herein mentioned have almost universally been provided with wooden heads, which when dropped has been found in practice to break the head loose 35 or to break the staves of the body of the receptacle thus spilling its contents.

I am aware that it is not new to provide 40 a metallic head for a wooden body portion, but so far as I am aware the only practical form of such constructions is that illustrated in my Patent #1,517,087 dated November 25, 1924, which is a construction that is well adapted to be applied to a wooden body portion having the usual croze located at the 45 inner side of its end, the said head being shaped to receive the ordinary shaped ends of the receptacle. This present invention is an improvement upon that patent as will be pointed out hereinafter.

50 In the accompanying drawings:—

Figure 1 is a perspective view of one end of a wooden receptacle having the improved metallic head applied thereto.

Figure 2 is a vertical cross section on the 55 line 2—2 of Figure 1.

Figure 3 is a horizontal section taken

through a part of the improved metallic head shown in Figure 1 the section being taken centrally through the securing means.

Figure 4 is a vertical sectional view of 60 the head of the receptacle with my improvement applied thereto, showing the method of detaching the metallic head from the body portion.

Figure 5 is a view showing the construction of means for applying the head to the end of the body of the receptacle.

Referring now to the drawings, 1 is the body of the receptacle that is composed of 70 wooden staves 2. These staves are preferably shaped to give a bilge to the receptacle, and 3 is the metallic head that is applied to the ends of the staves 2.

In my improvement the staves which form the receptacle are not provided with the 75 usual croze, nor are the ends of the staves of the usual construction, for instance as shown in my aforesaid patent. Therefore the staves are of the same cross sectional thickness throughout their length, and they 80 are therefore not weakened by a continuous annular croze as in my before mentioned patent.

In this improvement the said head is U-shaped in cross section as shown and its walls 85 4 and 5 are so shaped that it receives the said walled ends of the staves, thus providing a stave which is not weakened, as aforesaid, by the annular croze at its inner side, nor is the end of the stave weakened by reason 90 of having the inner side tapered outwardly from the upper edge of the croze to its end, as in my before mentioned patent. Therefore the metallic head has its inner and outer walls 3 and 4 substantially parallel, 95 whereas the inner wall as shown in my said patent is tapered upwardly and outwardly.

The metallic head 3 in my present construction has its inner wall perfectly plain when it is applied to the end of the receptacle, and is made of a sufficient depth 100 and of a shape to receive the extremities of the staves the ends of which are of uniform thickness with the balance of the stave. This metallic head being forced downward 105 tightly on the ends of the stave, the staves are therefore uniformly clamped by the metallic head.

The head being in position on the staves it is necessary to secure it there and in the 110 present improvement I accomplish this by piercing outwardly the inner flange 5 as at

- 6 which forces flanges 7 on the said openings into the body of the staves. It is well known that to pierce metal in this manner causes it to fray as shown in Figure 2, and the 5 frayed portion is in some instances partially turned laterally, though this is not essential in the present case. These piercings 6 are of a suitable number around the inner flange 5 of the cover, there being a sufficient number 10 to have them engage at least each stave, and preferably at least two of them pass into each stave as shown. However, it will be understood that the number of these punches depends upon the strength which it is desired 15 to give the receptacle. It is found in practice that by having at least two enter each stave that the keg will stand being dropped from platforms and stand the extreme rough use to which they are subjected in shipping without 20 breaking the ends of the staves, or breaking the head loose.

Preferably these openings 6 are placed sufficiently low in the flange 5 to engage the stave a sufficient distance below its end to 25 insure its permanent attachment to the receptacle.

In applying these improved heads, I utilize a tool constructed somewhat on the principle of my Patent No. 1,519,871 dated December 30 16, 1924, and reshape the outer edge of the dies 9 by providing the edge of the dies with a plurality of lateral projections 10, whereby when the dies are forced downward all of the punches are simultaneously made in the inner flange 5 of the head 3.

In addition to the additional strength of the staves, is the fact that the additional step in reshaping the ends of the staves is omitted, thus reducing the cost of the container, and 40 it requires much less strength or power to make the series of punched openings than it does to expand outwardly the whole inner edge of the cover as in my Patent No. 1,517,087. Therefore it is much easier to apply 45 this improved head than it is to apply the head shown in my last mentioned patent.

The metallic head having been thus applied to the receptacle or container, it is essential to provide means for detaching it 50 to permit access to its contents. Accordingly this is accomplished by hammering the horizontal portion 11 of the head substantially

at the points 12, which forces the horizontal portion 11 downward drawing the flanges 7 away from the staves thus permitting the 55 cover to be removed. This is the method that is utilized in my last mentioned patent. It is of course just as essential to be able to remove the head as it is to so construct it that it will stand all of the possible rough 60 usage to which it is subjected in shipping.

My present improvement has many advantages over the prior art, among which will be mentioned that it reduces the cost in that the ends of the staves are not subjected 65 to the additional step of shaping them; that the receptacle is much stronger in that the staves are not weakened by having their ends shaped with a croze as before mentioned, and the head is much easier attached to the receptacle than where a croze is used and the inner edge of the head provided with an outwardly extending portion fitting in the croze.

I desire it to be understood that the construction of the present improvement may be varied without departing from the invention so long as it is within a fair scope of the appended claim.

Having thus described my invention what 75 I claim and desire to secure by Letters Patent is:—

An easily attachable and detachable head for a wooden keg having its staves untapered, comprising a wooden body portion composed 80 of staves without tapered ends in combination with a head having a horizontal portion and extending outwardly from its horizontal portion, a U-shaped portion, the U being of 85 such size as to freely slip on the ends of the staves with its inner vertical wall in contact with the inner wall of the staves and its outer vertical wall outside of the said staves, and its inner vertical wall punched horizontally 90 outward into the untapered ends of the staves 95 to unite the head thereto, said head thereby adapted to be detached by hammering or forcing down its horizontal wall, thereby pulling the punched portions from the staves, substantially as described.

In testimony whereof I hereunto affix my signature.

GEORGE EUGENE MITTINGER.
